United States Patent Office

Des. 203,707
Patented Feb. 8, 1966

203,707

BOTTLE

John Piergallini, 141 W. Areba Ave., Hershey, Pa.

Filed May 6, 1964, Ser. No. 79,854

Term of patent 14 years

(Cl. D58—8)

The side of the bottle not shown is the same in appearance as the side shown.

I claim:

The ornamental design for a bottle, as shown and described.
